UNITED STATES PATENT OFFICE.

JOHN S. TOWNSEND, OF HARVEY, ILLINOIS, ASSIGNOR TO WHITING CORPORATION, OF HARVEY, ILLINOIS, A CORPORATION OF ILLINOIS.

SAND CUTTING AND SCREENING MACHINE.

Application filed May 12, 1920. Serial No. 380,714.

To all whom it may concern:

Be it known that I, JOHN S. TOWNSEND, a citizen of the United States, residing at Harvey, in the county of Cook and State of Illinois, have invented a certain new and useful Improvement in Sand Cutting and Screening Machines, of which the following is a specification.

It is well understood in the foundry art that after casting has been done in a foundry and the castings and flasks therefor are removed, the foundry room is left in a considerably disordered state as regards the molding sand in that it is in all sorts of shapes and piles and has refuse pieces of castings and other material such as wedges, pieces of broken cores, sprues, and gates mixed with it, and that before molding can take place the next day this sand has to be cleaned of this refuse, wet down, and thoroughly mixed and aerated or cut, and put in convenient piles. The object of this invention is to provide a machine preferably self-propelled which can be driven thru the foundry to automatically remove from it by screening all refuse material, thoroughly mix it after it has been tempered and finally deliver it in rows along the foundry floor in condition to be re-used in the further making of castings.

The invention consists in a machine for accomplishing this object which is a self-contained machine in that it can be controlled by a single operator riding upon it, and pass thru the foundry to perform all of the desired functions. More particularly the invention consists in novel means in the unitary machine for performing each of a separate elementary function entering into the complete operation of the entire machine. As the machine is quite complicated as a whole, containing many divisions and separate parts, the features of novelty will be more fully set forth in the specification and claims relating to each section or part of the machine.

Referring to the eight sheets of drawings in which the same numerals represent the same parts thruout the several views,

Figure 1 is a side view of a complete machine illustrating this invention in its preferred form.

Figure 2 is an end view of the machine

taken from the rear, i. e. the right hand end of Figure 1.

Figure 3 is a horizontal plan view partly in section taken across Figure 1, approximately just below the screen.

Figure 4 is a side elevation corresponding to Figure 1 but largely in section as to many of the parts.

Figure 5 is a detail view of the differential gear mechanism viewed in connection with the drive for the traction wheel.

Figure 6 is a vertical end view largely in section, taken at approximately the line 6-6 of Figure 1.

Figure 7 is an end view looking toward the back of the machine, taken on an irregular line in front of the sand screen and the driving wheels.

Figure 8 is a front view of the machine showing in detail the sand cutting elevating mechanism.

Figure 9 is a detail view of the friction drive mechanism and winding drum for controlling the electricity supply cable thru which the machine is provided with electric energy as it moves about the foundry floor.

Figure 10 is a plan view of a cam shown in section in the right hand end of Figure 11.

Figure 11 is a detail view largely in section of a friction clutch and worm gear drive therefor, the same appearing at approximately the center of Figure 4 at the lower left hand corner of the rotating screen.

The entire mechanism constituting this invention is mounted upon a horizontal frame consisting primarily of two oppositely disposed channel members 16 connected at the front of the machine by a yoke 18; in the middle by a cross member casting 20, and at the rear by a cross member casting 22.

Rigidly secured to and projecting from opposite sides of the lower portion of casting 20 are side flts 24 on which the main drive wheels 26 are journaled.

Depending from casting 22 are parallel spaced apart cross-lugs 27 between which is located a vertically rockable U-shaped yoke 28 journaled on a pin 30 bearing in the cross-lugs 27 on the frame 22. Thus yoke 28 is obviously adapted to rock in the vertical plane only and is so mounted in order to

allow the rear wheels 32 to adjust themselves to irregularities in the surface of the floor traveled. These wheels 32 are located one at each end of the yoke 28 and are supported thereon by the usual knuckle mounting, common in automobiles, viz, each wheel 32 is journaled on a horizontal shaft 34 projecting from a block 36, itself carried by a vertical shaft 38 journaled in spaced apart bearings 40 on the yoke 28.

The upper ends of these shafts 38 are also supported at their upper ends by brackets 42 extending from the yoke 28. As in common automobile practice, each shaft 38 has projecting from it a horizontal lever arm 44 and these are attached together by a connecting rod 46 so that the wheels 32 must move in unison.

The shaft 38 which is furthest from the operator's station hereafter described, is also provided with another horizontally projecting lever arm 48 to which is pivotally connected a connecting rod 50 running back across the machine. The opposite end of this rod 50 is pivoted to a lever arm 52 projecting from a rotatable vertical shaft 54 journaled in a casting mechanism 56 secured to the adjacent channel iron 16. Horizontally projecting from the upper end of this shaft 54 above the casting 56 is an operator's steering lever 58 provided with the usual locking mechanism 60 engaging a star wheel 62 of ordinary construction. This lever 58 is located within easy reach of the hand of the operator who stands upon a step 64 supported on the side of the machine by any suitable means, as for instance, the angles 66. It is obvious that the operator standing on this platform 64, which will be frequently referred to as the operator's station, can by rocking lever 58 backward and forward in a horizontal plane so move the lever mechanism described that the rear or steering wheels 32 are angularly moved with reference to the yoke 28, thus effecting steering of the machine in the ordinary way. The lever 50 is of such a length and the connections are sufficiently loose so that the yoke 28 and the wheels 32 can rock up and down in a vertical plane sufficiently to allow for irregularities in the floor or ground passed over by the machine without destroying the control of the shaft 54 and consequently the handle lever 58 on the wheels 32 in their different vertical positions.

Rigidly mounted on the hub of each wheel 26 is a gear wheel 68 meshing with a pinion 70. One of these pinions is carried on a shaft 71 and the other pinion is mounted on an oppositely disposed aligned shaft 72, the two being connected into a differential mechanism 74 shown in detail in Figures 5 and 7 but of standard commercial construction and therefore not described in specific detail. Any other standard differential

mechanism for this purpose may be used without departing from the invention. This differential 74 carries the usual external gear 76, meshing with a pinion 78 on a quill 80 supported in bearing 82 carried by brackets 83 attached to the cross member casting 20, heretofore described, by any suitable means, as for instance the bolts or screws 84. These bracket members 83 just described, as clearly shown in Figure 7, also afford bearing supports 86 in which the shafts 71 and 72 are journaled at their inner ends.

On the opposite end of the quill 80 from pinion 78 is a sprocket wheel 88 over which passes a sprocket chain 90 leading to the rear of the machine where it also passes over another sprocket wheel 92. This sprocket wheel 92 is rigid on shaft 94 journaled in four separate brackets or bearing frames 95, 96, 97 and 98 rising from cross member 22. This shaft 94 is selectively driven at two speeds forward and one speed backward by an electric motor 100 carried on a suitable bracket or platform 102 projecting from cross member 22. The connection between the motor 100 and shaft 94, permitting this speed and direction changing is as follows:—

Motor 100 carries pinion 104 which drives gear 106 carried on a short shaft 108 journaled in supports 95 and 96. Short shaft 108 carries a pinion 110 meshing with gear 112 on a shaft 114 carried in all four of the brackets 95 to 98, heretofore referred to.

On this shaft 114 and between supports 97 and 98 is mounted a double clutch 115—116. Between the members 115 and 116 which in the drawings represent standard parts of a commercial clutch mechanism of this type is the usual reciprocable double cone 118 shiftable backward and forward in the ordinary manner by a lever 120 convenient to the operator when standing on the operator's platform 64. As will be described, each of the members 115 and 116 has a train of gearing attached to it, and the operator in the usual manner selectively uses the desired one of these sets of gearing by properly shifting the lever 120 to correspondingly shift the cone 118.

Clutch member 116 is operatively connected with the gear 120 meshing with the gear 122 on shaft 94. When the parts are thrown to proper position so that the motor 100 operates this train of gears thru clutch member 116, the wheels 26 are driven in a clockwise direction as viewed in Figure 1, and the machine moves what is herein designated as rearwardly to draw the sand cutting and elevating mechanism away from the work. This train of gears 120 and 122, is in the particular case here illustrated so proportioned that the machine moves relatively fast in this direction, this in view

of the fact that no work is being done on the sand pile.

Clutch member 115 is operatively connected to pinion 124 meshing with the gear 126 on shaft 128 journaled in supports 97 and 98. This shaft 128 carries two pinions 129 and 130 of different sizes meshing respectively with gears 131 and 132 freely journaled on shaft 94.

10 Slidable lengthwise of shaft 94 between these gears 131 and 132 which are, by the way, of different sizes, is a clutch mechanism 134 shiftable by hand lever 136 under the control of the operator to cause said 15 clutch 134 to operatively engage either the gear 131 or the gear 132.

In actual practice the two trains of gears 130—132 and 129—131 are so proportioned that when one set of gears is in use the speed of the machine forward, viz, to the left, as viewed in Figure 1, is about twice as fast as when the other set of gears is in mesh. This allows the operator, by properly manipulating lever 136 to thus 25 selectively vary the forward working speed of the machine to take care of varying sand conditions on the floor or in the foundry where work is being done.

The motor 100 is supplied with electric current from any suitable source delivered to it thru a supply cable 138 connected at its end outside the figures shown to a fixed point source of energy—this cable 138 being divided on the machine into separate wires 35 140, leading to the motor 100 thru any sort of electric control mechanism ordinarily required in electric motors, the same not entering into this invention and therefore not shown in detail. In order to keep the 40 cable 138 reasonably tight in all positions of the machine in the foundry where it is working and thus avoid tangling of the cable with the machine, the mechanism shown at the top of Figure 2 and in detail 45 in Figure 9 is provided for constantly keeping the slack of the cable reeled up. The mechanism for doing this comprises a drum or reel 142 mounted on a shaft 144 journaled in suitable bearings 146 carried by the frame mechanism. This shaft 144 is rotated by a sprocket chain drive 148 from shaft 94 which it will be remembered 50 only rotates when the machine is being moved over the floor. The detailed mechanism driving sprocket chain 148 which performs its work is of considerable importance. The upper portion of the chain passes over a sprocket wheel 150 freely rotatable on shaft 144 but pressed into frictional 55 engagement with a disk 152, rigid on shaft 144 thru the action of a compression spring 154. The disk 152 carries on its face adjacent to the wheel 150 cork plugs 156 which afford a frictional yet yielding contact with the face of the wheel 150 so that

wheel 150 can rotate angularly with reference to the disk 152 but is retarded by the frictional engagement caused by the spring 154. The result of this construction is that assuming that chain 148 is operatively driven by shaft 94 the chain will cause wheel 150 to rotate disk 152 and thus wind up cable 138 just as long as there is slack cable to be so wound, but that when this operation is completed further rotation of shaft 94 merely causes wheel 150 to slip on disk 152 and thus prevent breaking injury to cable 128. This also allows for the unwinding of the cable 128 off from the drum 142 whenever the machine is running in the right direction for this. Under this condition disk 152 and the wheel 150 actually rotate in opposite directions.

Sprocket chain 148 is operated and connected to shaft 94 by passing over a sprocket wheel 158 which is detachably connectible to shaft 94 thru a latch member 160 which is also when rotated thru 180° from the operating position shown in Figure 2, a crank handle by which the operator 90 may rotate sprocket wheel 158 to independently manipulate drum 142 without reference to the rotation to shaft 94. This latch member crank handle 160 is for this purpose L-shaped, as shown, and is pivoted 95 to one side of the sprocket wheel 158 at 162 so that when the member 160 is rotated in a clockwise direction thru 180° from the position shown in Figure 2, the hand grip member 160a may be readily taken 100 hold of by the operator for operation as desired.

Tho it forms no part of this invention it may be stated that the current delivered by cable 138 reaches wires 140 thru three 105 controller rings 164 in continuous metallic contact with the usual controller fingers 166 clearly shown in Figure 2.

The sand screening or riddling mechanism is a metallic frame of standard construction having oppositely disposed metallic rings 168 and 170 spaced apart by connecting rods 172 between which is mounted the usual screen material 174. The forward end of this riddle is mounted on 115 rollers 176 carried by the frame of the machine. The ring 168 rotates upon these rollers.

The rear ring 170 is carried by a suitable spider 178 from a hub 180 rigid upon 120 a shaft 182 journaled in the bearings 184 formed at the upper end of member 97. The right hand end of shaft 182 carries a bevel gear 186 driven by a bevel pinion 188 mounted on shaft 190 in turn carrying a gear 192 driven by a pinion 194 mounted on a clutch 196 selectively driven on shaft 114. This clutch member 196 is driven by a clutch cone 198 controlled by a hand lever 200 under the control of the 130

operator. By properly manipulating this lever the operator can cause the riddle to be rotated or remain at rest as he desires. This lever 200 also simultaneously sets the 5 elevating mechanism to be hereafter described, in operation. This latter operation is accomplished thru the fact that the shaft 190 carries a sprocket wheel 202 over which passes sprocket chain 204 leading to the 10 elevating mechanism, said chain passing over another sprocket wheel 206 mounted on the main shaft 208 which drives the elevator mechanism to be hereafter described.

15 Shaft 208 is journaled in suitable bearings 210 supported on opposite sides of the frame in connection with member 18, heretofore described, and diagonal braces 212, rising from the side channel irons, clearly shown in Figure 1.

20 Rotatably mounted on shaft 208 intermediate between the side members of the frame 18 are two block bearings 214, clearly shown in Figure 4. Slidably mounted on opposite sides of each one of these block bearings is an elevator frame member 216 made up of two separated parallel members connected by spacing members 218. This frame member 216 is movable longitudinally of the bearing block thru the agency of a rotatable screw 220 bearing at one end adjacent the block bearing and threaded thru a stationary lug 222 on a rigid cross member 224 of the elevator frame. By applying a wrench to the non-circular end 226 of the screw it may be rotated in either direction thus causing the block bearing and consequently the entire elevator frame to move toward or from the bearing block 214 and consequently the shaft 208. As there is one of these screws 220 for each side of the elevator it is obvious that by rotating both screws the entire elevator will be raised or lowered with reference to the shaft 208. This is done for the purpose of tightening the respective sprocket chains 228 which pass over sprocket wheels 230 at the top of the elevator and 232 at the bottom of the elevator. The two 25 sprocket chains 228 have suitably connected to them transverse elevator buckets 234 adapted when the sprocket wheels 230 and 232 are rotated in a clockwise direction, as viewed in Figures 1 and 2, to scrape up material at the bottom of the elevator, carry it up the outside or left hand side of the elevator and over the top of the sprocket wheels 230 at a sufficient speed to cause the contents of the bucket at the top to be discharged into the screen or riddle, heretofore 30 described.

35 The sprocket wheels 232, heretofore referred to, are carried upon a horizontal shaft 236 journaled in four bearings 237, 238, 239 and 240 supported from the lower

end of the elevator frame. The shaft 236 is of considerably greater length than the width of the main elevator frame, viz the distance between the members 218. This surplus length of shaft 236 is occupied by 40 rotatable sweeping blades or "ironmen" 242 well known in the art so positioned and arranged that the blades on each set sweep sand or other material engaged by them toward the center of the device into the path 45 of travel of the buckets 234 so that the buckets can take up the material gathered by the ironmen and deliver it into the riddle.

50 The elevator mechanism is positioned as to height with reference to the floor or ground by being rocked angularly about the axis of shaft 208. This movement is accomplished by placing on opposite sides of the elevator frame projecting trunnions 244 on each of which is journaled a generally horizontal bar or plate 246 extending inside the main frame of the machine and provided at its inner end with an elongated slot 248 thru which passes a shaft 250 55 carrying a pinion 254 meshing with a rack 256 mounted upon and carried by the member 246, the result being that when shaft 250 is rotated, as hereafter described, the pinion forces rack 256 to travel horizontally over the pinion, thus reciprocating in either direction desired, the member 246 and consequently the elevator mechanism. The shaft 250 is driven in either direction at the will of the operator, thru any suitable sort of a mechanism one form of which is as follows:—The shaft 250 carries a worm gear 260 which meshes with a worm 262 (Figure 11). Non-rotatively, but reciprocatively mounted on a shaft 264 thru the agency of a spline 266 is a sleeve 268. This sleeve carries a pair of oppositely disposed bevel friction disks 270 and 271 between which is placed a bevel disk 272 on a shaft 274 carried on supports 276, Figure 7. This shaft is connected by sprocket chain mechanism 278 to shaft 114, heretofore described, so that rotation of shaft 114 continuously rotates friction disk 272 with the result that when the operator, by means hereafter described, moves the bevel disk 271 into engagement with disk 272, the shaft 264 will rotate in one direction and that when the operator moves the sleeve so that disk 270 is in engagement with disk 272, then the shaft 264 will be rotated in the opposite direction. This ability to rotate shaft 264 in opposite directions makes it possible for the operator to, thru mechanism described, rock the elevator mechanism about shaft 208 as a center and thus move the ironmen 242 and elevator to proper working position adjacent to the floor, or to elevate them a substantial distance off from the floor as desired.

The special advantage of using a friction drive between the respective gears 272 and 270, and 272 and 271 is to permit slipping, thus preventing breaking when the elevator is moved to the limit of its stroke in either direction as defined by the length of the slot 248 and also to allow for trouble in the event the operator attempts to raise the elevator against obstructions on the floor in 10 the path of the adjacent bucket 234.

The sleeve 268 and attached parts, heretofore, described, is reciprocated along the shaft 264 thru the lever and cam mechanism shown in Figure 10 and at the right hand 15 end of Figure 11. A lever 280 is rigidly attached to a collar 282 rotatable on the sleeve 268 and held against endwise movement thereon by a collar 284 held in place by a pin 286. This collar 282 is rotatable 20 inside of a bearing 288, suitably supported. Thru this bearing 288 is an elongated cam slot 290 thru which passes a pin 292 entering collar 282. From an inspection of the parts just described it will be seen that by rock- 25 ing the lever 280 and consequently partially rotating collar 282 the collar must travel lengthwise of itself a distance equal to the length of a cam slot 290, and this forces the sleeve 268 to travel lengthwise 30 an equal distance (because the collar 282 bears on the collar 284 at one end and on the disk 271 at the other).

Lever 280 is reciprocable, thru a connecting rod 294 manipulated by a hand lever 296 in easy reach of the operator. In practice the operator takes hold of this hand lever and holds it in the required position to engage disks 272 and 271, or 35 272 and 270 as required to make the move- 40 ment of the elevator he desires. The rest of the time he leaves the lever alone and the frictional engagement only between the disks, heretofore described, prevents accidents.

One important feature of the invention 45 is to provide easy means for insuring very short turns of the machine in passing over the foundry floor. This is accomplished by providing each driving wheel 26 with an 50 independent brake so that by applying the brake to one driving wheel, leaving the other free, the machine will turn very rapidly about the braked wheel as a pivot. This 55 brake mechanism consists of a pair of independent brake shoes 298 and 300, independently operated by independent foot treadles 302 and 304 within easy reach of the operator. In carrying out the details of this 60 device both brake shoes operate about the central axis of the cross shaft 306. This shaft is the operating member for brake shoe 298 which is rigidly attached to it and is merely the pivotal axis for the brake- 65 shoe 300. Obviously treadle 304 is connected to lever 308 to rotate the shaft 306 to

move brake shoe 298. Similarly treadle 302 is connected to drive brake shoe 300.

The body of the screen or riddle is enveloped on its opposite sides by dirt retaining walls 310 and 312 terminating at their 70 bottom in a downwardly and rearwardly extending chute 314 adapted to direct sand passing thru the riddle to the end of the chute into a pile midway between the supporting wheels of the machine.

Across the machine at a point below the riddle and leading to one side thereof is a coarse material chute 316 adapted to receive coarse material which does not pass thru the riddle and carry it off to the side 80 of the machine. In the particular case illustrated in Figure 2 the end of this chute is detachably closable by door 318 adapted to retain this coarse material at the end of the chute until the operator is ready to remove it from the machine.

Operation.

The motor 100 runs continuously in one direction. The operator by properly manipulating the lever 120, as described, causes the entire machine to travel backward or forward, as he desires. Before starting forward or while the machine is running extremely slow he can by manipulating the lever 136 change the speed. By manipulating lever 200 the operator causes the motor to operate the screen and elevator. By reversing this lever he stops these. By properly manipulating the lever 296 the operator 90 raises or lowers the elevator with reference to the floor, the parts being locked in desired position by the well known locking action of the worm and gear 260-62. In addition to the foregoing the motor automatically takes care of the drum 142 controlling the supply cable for electricity leading to the machine. In addition the operator steers the machine thru lever 58 and by using one or the other of the treadles 302 and 304 facilitate turning action. The result of the foregoing 95 is that the compact machine shown and described can be moved in any direction, and do the work required, with a maximum efficiency.

Having thus described my invention what I claim as new and desire to secure by Letters Patent, is—

1. In mechanism of the class described, a supporting frame, an elevator mechanism pivotally mounted near the top of the frame so that its lower end can swing toward and from the frame, and a pair of rods on opposite sides of the elevator slidably approximately horizontally thru the frame, a rack on each rod, a shaft mounted in the frame having a pinion adjacent to each rack, a power shaft adjacent to the first mentioned shaft, a reversible friction drive mechanism 120 between the power shaft and the first men- 125

tioned shaft, and means for selectively moving said friction drive mechanism to determine in which direction the power shaft shall move the first shaft and consequently 5 the elevator, for the purposes set forth.

2. In mechanism of the class described, a supporting frame, wheels supported for movement over a foundry floor, a rotatable riddle carried by the frame, an elevator 10 pivotally mounted adjacent to the end of the riddle equipped with sand cutting means for gathering sand onto the elevator from which it is delivered to the riddle, a single motor carried on the machine, means by 15 which said motor drives said riddle and said elevator, means by which said motor propels the supporting wheels and consequently the machine along the floor, variable gear mechanisms between the motor and the wheel supporting mechanism by which the operator in a single operator's station on the 20 machine may vary the direction and speed of the machine, and means controlled by the operator of the machine at said station for starting and stopping reversing the direction, and varying the speed of the machine, starting and stopping the riddle and elevator for varying the angularity of the elevator. 25

3. In mechanism of the class described, a supporting frame, wheels supported for movement over a foundry floor, a rotatable riddle carried by the frame, an elevator

pivots mounted adjacent to the end of the riddle equipped with sand cutting means 30 for gathering sand onto the elevator from which it is delivered to the riddle, a single motor carried on the machine, means by which said motor drives said riddle and said elevator, means by which said motor propels 40 the supporting wheels and consequently the machine along the floor, variable gear mechanisms between the motor and the wheel supporting mechanism by which the operator in a single operator's station on the 45 machine may vary the direction and speed of the machine, and means controlled by the operator of the machine at said station for starting and stopping reversing the direction, and varying the speed of the machine, starting and stopping the riddle and elevator for varying the angularity of the elevator, this in combination with an electric supply cable leading from a fixed support to the machine, and an automatic winding 50 mechanism for the cable driven by the machine, keeping the cable tight in all positions of the machine within the length of the cable.

In witness whereof, I have hereunto subscribed my name in the presence of two witnesses.

JOHN S. TOWNSEND.
